United States Patent Office

Des. 210,844
Patented Apr. 23, 1968

210,844

PITCHER

Victor F. Anderson, 13 W. Mantua Ave.,
Wenonah, N.J. 08090

Filed Sept. 21, 1967, Ser. No. 8,678

Term of patent 14 years

(Cl. D44—21)

FIG. 1

FIG. 2

FIG. 4

FIG. 3

FIG. 5

I claim:

The ornamental design for a pitcher, as shown and described.
